US0D1049165S

(12) **United States Design Patent** (10) **Patent No.:** **US D1,049,165 S**
(45) **Date of Patent:** **** Oct. 29, 2024**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Alan C. Dye**, San Francisco, CA (US);
Joseph Mark Willoughby Luxton, San
Francisco, CA (US)

(73) Assignee: **Apple Inc.**, Cupertino, CA (US)

(***) Term: **15 Years**

(21) Appl. No.: **29/927,945**

(22) Filed: **Feb. 7, 2024**

Related U.S. Application Data

(63) Continuation of application No. 29/878,548, filed on Jun. 23, 2023, now Pat. No. Des. 1,035,689, which is a continuation of application No. 29/820,589, filed on Dec. 22, 2021, now Pat. No. Des. 993,974, which is a continuation of application No. 29/746,569, filed on Aug. 14, 2020, now Pat. No. Des. 939,528.

(57) **CLAIM**

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
